UNITED STATES PATENT OFFICE

JAN DROPINSKI, OF SAN FRANCISCO, CALIFORNIA

SHADE

Application filed September 24, 1930. Serial No. 484,101.

This invention relates to shades.

It is the primary object of the invention to provide a partly transparent shade, on one side of which appears an outline design of a decoration, means being provided adjacent to the other side of the shade to transmit rays of light thru openings or slots corresponding to fine detail lines of design of the decoration outlined on the shade, the outline design being the decoration of the shade when the back side thereof is not illuminated, but when light shines on the back side of the shade the decoration is formed by lines of light rays passed therethrough.

Particularly it is an object of this invention to provide a shade formed of an opaque stencil, the slots of which represent a detail line design of a decoration, and a transparent covering on one face of the stencil having a large outline design thereon corresponding substantially to the boundaries of the design of the stencil for decorating the shade when there is no light shinning thru the stencil, other times the light rays passing through the slots and openings of the stencil forming the detail line design within the said boundaries; the said shade being adapted to be bent and arranged in a desired form such as a lamp shade, to form a different decoration on the lamp at daylight than the design and decoration appearing thereon at artificial light within the lamp.

Other objects and advantages are to provide a shade that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

The invention is clearly illustrated in the accompanying drawing wherein

Fig. 1 is a face view of a flat shade constructed in accordance with my invention.

Fig. 2 is a cross section view of the shade on an enlarged scale, the section being taken on the line 2—2 of Fig. 1.

Fig. 3 is a side view of a lamp shade constructed in accordance with my invention, the outer layer being shown partly broken away.

Fig. 4 is a fragmental rear view of the stencil of the shade.

In its general organization the invention includes an opaque stencil 6, having a design partly cut out therefrom and bent away from the plane of the stencil so as to leave a clearance 7 adjacent the edges of the cut out design, to allow light rays to shine therethrough. The bent away flaps 8 are formed to represent parts of the detail decoration desired, such as the petals or leaves of flowers, or the like.

On the smooth side of the stencil 6 and over the cut out design, is suitably secured a transparent layer sheet 9, on which the said light rays reflect the lines of the design as cut out from the stencil 6. The transparent layer 9 may cover the entire outer surface of the stencil, or it may be arranged only opposite the portions of the stencil where the designs are cut. In both instances the transparent layer is so arranged and colored as to correspond to the outer boundaries or contour of the particular group designed on the stencil. These outline areas 11 appear as a somewhat futuristic decoration when there is no illumination on the inside face of the stencil 6. These areas outlining the general design are surface shaded for color in the drawings to illustrate the attractive decoration that is obtained thereby.

When light is shining on the inner side of the stencil 6, the fine lines of light transmitted through the clearances 7 reflect a fine illuminated detail design onto the layer design areas 11 thereby combining therewith to form the illuminated decoration of the shade.

The shade A shown in Fig. 1 can be hung in front of a window pane or the like as a decorative picture or the like, and present a different design at night than in day light when the sun shines through the stencil 6. The same effect can be accomplished by artificial light.

In Fig. 3 the shade is bent into a frustoconical lamp shade B and the large area or boundary design is the day light decoration of the shade, while the stencil design 12 reflects within the area 11 only when the electric light within the shade is illuminated.

The fine decoration reflected into the area 11 is also shaded by reason of the partial reflection of light from the convex side of the flaps 8. Near the clearance 7 the light shines bright, while gradually shaded light spots are reflected to appear adjacent each clearance 7, giving depth to the design.

The section in Fig. 2 is taken on the stencil 15 at a point where the design represents a pansy 14, the petals 16 of which are cut out of the stencil at their outer periphery and are bent away toward the back of the stencil, all petals converging to the center of the 20 pansy. Thus, when light is reflected on the stencil, finely shaded petals are reflected on the colored area 14 to coat therewith in presenting an attractive illuminated design.

In some instances, if so desired, the inner 25 surface of the stencil 6 may be also covered by a transparent sheet of material. In all embodiments, the outer layer 9 presents a decorative design when no light is shining on the back of the stencil, and when light is 30 shining on the stencil, the decoration changes, and a novel and different illuminated decoration appears within the decorative areas of the outer layer 9.

Having thus described this invention, what 35 I claim and desire to secure by Letters Patent is:

1. A shade comprising an opaque stencil having a design cut thereon, the edges of the design being bent away to the back side of 40 the stencil out of the plane of the same to permit light rays from the rear of the stencil to shine through, a transparent cover on the other face of the stencil having a design thereon substantially corresponding to the 45 boundaries of the group of stencil design to form a decoration of the shade independently of the stencil cuts at one time, and coating with the stencil design reflected thereon through the cut edges of the stencil design 50 from a source of light behind the stencil to form a different and illuminated decoration.

2. A shade comprising an opaque stencil having a design cut thereon, the edges of the design being bent away to the back side of 55 the stencil out of the plane of the same to permit light rays from the rear of the stencil to shine through, a transparent cover on the outer face of the stencil having a design thereon substantially corresponding to the boundaries of the group of stencil design to form a 60 decoration of the shade independently of and different from the stencil cuts at one time, and coating with the stencil design reflected thereon through the cut edges of the stencil design 65 from a source of light behind the sten-

cil, the stencil design forming detail lines to complement and shade the outline and face of the decoration on the transparent cover.

3. In a lamp shade an opaque stencil bent and secured in the shape of a lamp shade, and 70 a transparent covering on the outside surface of the lamp shade, said covering having a decorative design thereon to be complemented by the stencil design reflected onto the covering when a light inside of the shade is illuminated, the design on the covering being formed by a plurality of separate areas representing substantially the outlines of the group designs cut in the stencil, so that the 75 stencil designs are reflected into the corresponding areas on the covering, the edges of the stencil design being bent out of the plane of the stencil and inwardly of the shade to form convex reflecting surfaces at the edges as well as the body of said cut edges, thereby 80 to reflect graduated light spots onto the said areas to give depth to the design.

In testimony whereof, I have hereunto set my hand at San Francisco, California, this 3d day of September, 1930.

JAN DROPINSKI.
